DISPERSION MILL

Frank A. Sullivan, Salem, Mass., assignor to The
Tri-Homo Corporation, Salem, Mass., a corpora-
tion of Massachusetts

Application June 25, 1949, Serial No. 101,369

4 Claims. (Cl. 241—163)

1

This invention relates to improvements in dispersion mills of the general type suitable for performing grinding, milling and homogenizing operations in the processing of various materials and substances in liquid and paste forms, such as paints, pigments, dye stuffs, gums, fatty acids, and the like. More particularly it provides improvements in such mills whereby materials and substances to be acted upon are more effectively induced into the mill and more effectively and efficiently treated before discharge, as compared with any prior comparable mill of which I am aware.

Dispersion mills of the general type to which the invention relates ordinarily accomplish their grinding, milling and homogenizing functions as the result of the action of closely related surfaces of two members at least one of which has rotary motion relative to the other, the material or substance being treated passing between the closely related, relatively moving surfaces and being ground, mixed, and its constituents generally comminuted, prior to discharge from the mill. Various proposals have been advanced heretofore directed toward accomplishing a thorough and satisfactory reduction of all solid particles that may be present in any particular material or substance undergoing treatment in a mill. It has been proposed, for example, to provide two and even more stages of grinding and pulverizing action within the mill, with the material or substance passing successively through the different stages of grinding and pulverizing action before delivery from the mill. However, notwithstanding the prior efforts to satisfactorily reduce and pulverize all solid particles in materials or substances being treated, none of the prior comparable mills, so far as I am aware, accomplishes complete and satisfactory elimination of objectionable solid particles. One characteristic of such mills which aggravates the problem of failure to eliminate objectionable solid particles may be traced to the desirability of having the working surfaces of at least one of the grinding members of the mill of a nature to itself loosen particles of its surface material in the course of operation of the mill, and these dislodged solid particles get into the stream of the material or substance undergoing treatment. The number of such dislodged solid particles may be considerable in any particular batch of treated material, and they ordinarily are hard enough to resist pulverization in the mill. Rather, their nature is such that they cause other particles to be dislodged from a grinding surface. This is especial-

2

ly true when abrasive stones are employed as the grinding members, abrasive particles breaking away from the surfaces and being present in objectionable sizes and number in the treated materials and substances delivered from the prior mills which have employed abrasive stones.

Also, feed of materials and substances into the prior comparable mills has been slow and sluggish, especially when the materials have been of thick paste consistency, requiring screw conveyors and the like in the inlet passage to move the material into the action of the grinding members of the mill.

It is among the objects of my present invention to provide a dispersion mill wherein the main grinding, milling and homogenizing action is accomplished between relatively closely related rotor and stator surfaces between which the material or substance being treated is caused to move outwardly by centrifugal force, and wherein means is provided at a working face of the rotor for creating suction tending to draw the material or substance into the space between the closely related rotor and stator surfaces.

Another object is to provide a dispersion mill wherein the main grinding, milling and homogenizing action is accomplished by abrasive rotor and stator surfaces between which the material being processed is caused to flow by centrifugal force, and wherein abrasive-resistant rotor and stator surfaces effect a final pulverizing action on any solid particles which may have escaped adequate reduction in the main action of the mill.

A further object is to provide a dispersion mill having coating abrasive surfaces between which the main grinding, milling and homogenizing action occurs, and wherein a final pulverizing action occurs between abrasive-resisting surfaces, subsequent to the main action, with means for simultaneously adjusting the spacing of the abrasive surfaces and of the abrasive-resisting surfaces.

It is moreover, my purpose and object generally to improve the structure, efficiency and effectiveness of dispersion mills and the like, and more especially such mills wherein it is desirable to pulverize abrasive particles which may become dislodged from an abrasive surface and become mingled with the material being processed.

In the accompanying drawing:

Fig. 1 is a side elevation of a dispersion mill embodying features of my invention, portions thereof being shown in medial cross-section;

Fig. 2 is a cross-sectional view on line 2—2 of Fig. 1; and

Fig. 3 is a fragmentary cross-sectional view on a larger scale, showing the coating pulverizing surfaces which form the annular discharge passage around the periphery of the rotor.

Referring to the drawing, any suitable base 10 may support the spaced, vertically disposed risers 12, 14 which, in turn, support the tubular sleeve 16, one end of the sleeve seating rotatably in an annular recess 18 in riser 14, and the other end portion of the sleeve being exteriorly threaded at 20 and screwed into the interiorly threaded shank 22 of a housing indicated generally at 24, the shank 22 extending into an opening 26 in riser 12 and being secured against movement therein by the set screw 28.

A shaft 30 extends through sleeve 16, being journalled at 32 in riser 14, and having ball-bearing support at 34 in the opposite end portion of sleeve 16, the shaft extending out of this end of the sleeve into the interior of housing member 24 where it is equipped with the wheel-carrying plate 36. Shaft 30 may be driven from any suitable source of power as through the medium of a belt (not shown) trained over a pulley 38 which may be fixed on shaft 30 adjacent to the riser 14.

The housing 24 preferably will be at least in part of double wall construction to provide space 40 between walls for circulation of water for cooling purposes, one wall 42 of the housing being removable and having an opening 44 therethrough axially aligned with shaft 30. The delivery end of a conduit 46 is removably secured in opening 44, the conduit leading from a hopper 48 or the like from which material to be processed flows through the conduit into the interior of housing 24.

A feature of the invention resides in means 40 interiorly of housing 24 whereby a more effective grinding and homogenizing action on the material takes place, with a final and ultimate treatment of the material which pulverizes any solid particles which may have escaped the main treatment without being pulverized.

According to the invention, a substantial annular ring 50 of abrasive material is secured, as by bolts or screws 52, to the interior of wall 42 of the housing, the ring being concentrically arranged relative to the axis of shaft 30, and constituting the stator grinding member. An abrasive wheel 54, constituting the rotor grinding member, is secured to the wheel-supporting plate 36 as by screws 56 and a larger central screw 58, the wheel 54 being concentric with shaft 30.

Also mounted on the housing wall 42 is the inwardly projecting annular member 60 which encircles the abrasive ring 50 and the abrasive wheel 54 at their peripheral regions, being spaced a little outward from their peripheries opposite their adjacent faces and extending with slight inclination of its interior surface opposite the main peripheral surface of wheel 54, so that material delivering from between the adjacent opposed surfaces of the ring and wheel is caught and re-directed by the member 60 whereby the material is directed and guided generally toward the periphery of the wheel-carrying plate 36, escaping between the member 60 and the plate 36 into the outlet passage 62 at the bottom of housing 24 and discharging thence into the chute 64.

The face of wheel 54 which is toward ring 50 preferably is provided with a series of equally spaced radial grooves 66. These have relatively

short radial extent with part of their extent opposite a face of ring 50 and part opposite the central space within the ring, whereby material delivered into the central ring space and entering between the opposed ring and wheel faces is caught in substantial amounts in the radial grooves 66 and forcibly carried around on the wheel, with centrifugal force urging it forcibly outward toward the periphery of the wheel. In this action, the walls of the grooves 66 create a substantial suction as the wheel rotates, and the suction effect tends to draw material into grinding co-action between the ring and wheel, a result which is of particular importance when the material being processed is viscous and sluggish.

The spacing of the coating surfaces of ring 42 and wheel 54 may be readily adjusted by manual rotation of sleeve 16 which, because of its threaded engagement at 20 with shank 22 of housing 24, will cause the housing and abrasive ring 50 to move in direction to bring the ring and wheel closer together or further apart, depending upon the direction of rotation of sleeve 16, assuming that set screw 28 first will be loosened to release shank 22. As herein represented, the rotation of sleeve 16 may be effected by manual rotation of a shaft 68 journalled in a support 70 rising from base 10 between the risers 12, 14, the shaft 68 having a worm 72 fixed thereon and in mesh with a worm gear 74 fixed on sleeve 16.

The use of abrasive surfaces for effecting grinding and homogenizing treatments of various materials and substances has definite advantages as regards efficiency and effectiveness of any particular processing procedure. Heretofore, however, there have been disadvantages accompanying the advantages. Perhaps the more serious disadvantage has been the fact that the abrasive surfaces inherently are of a nature to wear away in service with resulting deposition of abrasive particles in the material being processed, and these abrasive particles are so hard that they ordinarily pass through the processing apparatus without appreciable reduction in their sizes. Actually their inherent hardness tends to dislodge other abrasive particles from the abrasive surfaces, and their presence in the delivered material or substance is highly objectionable in many cases. For example, the presence of even a relatively few of these solid and hard abrasive particles is readily noticeable in paint as soon as the paint is brushed on a surface.

My present invention provides means for positively pulverizing such abrasive particles, and any other solid particles escaping the main grinding and homogenizing action of my apparatus. As best seen in Fig. 3, the periphery of the wheel-carrying plate 36 is shaped to provide the stepped inclined surfaces 76, 78 which may be treated or coated to provide extremely hard abrasive-resistant surfaces. "Stellite" is a preferred material for these surfaces 76, 78, it being highly resistant to abrasion. Similar surfaces 80, 82, of "Stellite" or comparable material, are provided on the annular member 60 which projects from housing wall 42 as previously described, this member 60 having annular extent for encircling at least a substantial portion of the periphery of plate 36, and its "Stellite" surfaces 80, 82 having relations to the comparable surfaces 76, 78 of plate 36 such that these hard, abrasive-resisting surfaces define an annular discharge passage at the periphery of plate 36 whose annular outlet may be restricted to such an extent as to bar the passage of any solid particles, and this restricted

outlet may be adjusted as a result of the earlier described adjustment of the spacing of the coacting surfaces of ring 42 and wheel 54. Hence, assuming rotation of wheel-carrying plate 36 and an adequate supply of material to be processed delivering between disk 42 and wheel 54, the material, under centrifugal force moves outward between the disk and wheel surfaces, being discharged against annular member 60 and redirected and guided thereby to the annular discharge passage formed by the surfaces 76, 78 and 80, 82. The material is propelled with considerable pressure from behind, and the annular outlet will be adjusted to permit escape of material which has been adequately reduced and freed of solid particles. Any solid particles coming into the annular discharge passage are pulverized by being driven between the hard "Stellite" surfaces 78, 82. The considerable pressure, built up from behind, positively forces the solid particles into the pulverizing action of the surfaces 78, 82, thereby avoiding clogging of the outlet as well as assuring that no appreciable or objectionable particles of solid matter can be mingled with the processed material delivering to the outlet passage 62 and chute 64, assuming a proper adjustment of the annular outlet passage at the periphery of plate 36.

It will be apparent from the foregoing description, in connection with the drawing, that I have greatly improved the efficiency and effectiveness of dispersion mills by providing rotor and stator abrasive surfaces between which the main processing of material is effected, with means at the rotor surface for strongly inducing flow of the material into the grinding and homogenizing action of the apparatus. Also, I have provided an extremely effective pulverizing action prior to discharge of the processed material which greatly improves the delivered product and which pulverizes any solid particles which may have escaped adequate reduction by the abrasive elements, especially such particles of abrasive material as may have been dislodged from a surface of an abrasive element.

I claim as my invention:

1. In a dispersion mill, a relatively fixed housing, a relatively thick ring of abrasive material fixed on a wall of the housing interiorly of the housing, a rotor plate within the housing, a relatively thick disk of abrasive material mounted on said rotor and disposed opposite and in slightly spaced relation to said fixed ring of abrasive material whereby adjacent generally parallel surfaces of said ring and disk define a passage for centrifugal movement of material between them, means for delivering material through a wall of the housing into the central opening in said ring whence it enters between said generally parallel surfaces of the ring and disk, an annular member fixed on a wall of the housing and relatively closely surrounding the peripheries of said ring and disk, said rotor plate having an annular peripheral portion outward of the periphery of said abrasive disk, and said fixed annular member coacting with the periphery of said abrasive disk to provide an annular passage leading to said peripheral portion of the rotor plate and having an annular edge portion coacting with said peripheral portion of the rotor plate to provide a restricted annular outlet around said peripheral portion of the rotor plate, and abrasive-resistant material on the coacting surfaces of said restricted outlet whereby they are more resist-

ant to erosion than the coacting surfaces of said abrasive ring and disk.

2. A dispersion mill comprising a housing, a stator member secured interiorly on a wall of the housing, said stator member having a surface disposed generally in a vertical plane, a rotor member rotatably mounted in the housing and having a surface disposed in a vertical plane in spaced relation to the said surface of the stator member, said surfaces being in relatively close generally parallel relation and adapted to coact in processing material passing between them, and one of the coacting surfaces being an abrasive surface, said stator member having a central passage therethrough communicating with the space between said surfaces of the members, means for conducting material to said central passage whence it enters the space between said coacting surfaces and passes outwardly by centrifugal force, means adjustably mounted within the housing and extending all around the periphery of the rotor member in spaced relation thereto and having extent also opposite said space between the coacting surfaces, whereby material passing outwardly from between the coacting surfaces engages said adjustably mounted means and is re-directed and guided thereby in direction generally horizontally on a course leading between a wall of said adjustably mounted means and the periphery of said rotor member, said wall of the adjustably mounted means and said periphery of the rotor member having converging extent to a restricted annular discharge region at the periphery of the rotor member, abrasive resisting material surfacing said converging portions of the wall of the adjustably mounted means and the periphery of the rotor member, and means for simultaneously reducing the space between said vertical and parallel processing surfaces of the stator and rotor members and between said converging walls of said adjustably mounted means and the periphery of the rotor member.

3. A dispersion mill comprising a housing, an annular stator member fixed interiorly on a wall of the housing and having a generally vertically disposed abrasive surface, an annular rotor member rotatably mounted within the housing and having an abrasive surface in opposed relation to and in slightly spaced general parallelism with the abrasive surface of the stator member, said stator member having an axial passage therethrough for entrance of material to said space, an annular member extending around the stator and rotor members and providing, with the periphery of the rotor member, a flow passage for material along the periphery of the rotor member in generally horizontal direction, said flow passage having walls converging to a restricted annular outlet, and the surfaces of the annular restricted outlet being of material highly resistant to abrasion, whereby solid particles entering the annular restricted outlet become pulverized by the grinding coaction of said abrasive-resistant surfaces, and means for controlled adjustment of said stator member toward said rotor member to simultaneously reduce the space between said vertically disposed generally parallel abrasive surfaces of the rotor and stator members and between said abrasive-resistant surfaces of said annular restricted outlet.

4. A dispersion mill comprising stator and rotor members having opposed abrasive surfaces spaced slightly apart in general parallelism to provide a flow passage for material entering between them, said members being relatively adjustable

7 to vary the width of said flow passage whereby the coating abrasive surfaces may be set to effectively process the material entering between them and moving outwardly between them by centrifugal force, an annular member on said stator member in relatively close surrounding relation to the peripheries of the stator and rotor members, against which annular member the outwardly moving material is thrown and between which and the peripheral portion of the rotor member the material is guided, said annular member having an abrasive-resistant surface converging toward a peripheral portion of the rotor member, and the rotor member having an abrasive-resistant surface opposite said converging surface of said annular member, said abrasive-resistant surfaces of the annular member and the rotor member coating to provide a material-pulverizing restricted annular discharge opening at the periphery of the rotor member whereby any solid particles in the material thrown against said annular member become pulverized in passing through said restricted annular discharge opening, and means for moving the stator member

5 axially toward the rotor member to simultaneously reduce the width of said flow passage between said opposed abrasive surfaces of the rotor and stator members and of said annular discharge opening at the periphery of the rotor member.
